UNITED STATES PATENT OFFICE

JOHN PRESTON MINTON, OF WHITE PLAINS, NEW YORK, ASSIGNOR TO RADIO CORPORATION OF AMERICA, A CORPORATION OF DELAWARE

LOUD SPEAKER

Application filed June 12, 1935. Serial No. 36,568.

The invention relates to devices for producing sounds by electric current and has for its principal object to improve the quality of sounds emitted and to increase the intensity thereof. A more specific object of the invention is to provide an acoustic device from which sounds will be emitted from the front part of the diaphragm only.

Still another object of the invention is to provide an acoustic device in which the sound will be emitted from the front part of the diaphragm only, any tendency to interference between sound waves from the front and rear of the diaphragm being overcome.

It is well known that the construction of many types of acoustic devices of the loud speaker type forms a fairly large cavity behind the vibrating diaphragm and it is often necessary or desirable to enclose this cavity by the casing of the device. This closed cavity has certain undesirable effects on the intensity and quality of sound emitted for several reasons. In the first place under certain conditions sound energy may flow from both sides of the diaphragm thereby theoretically at least, reducing by one half the useful sound energy, as of course, ordinarily only the sounds emitted by the front part of the diaphragm are useful. Another bad effect of such a closed cavity may be traced to the casing itself which may have sufficient resiliency to cause it to vibrate in sympathy with the vibrating column of air entrapped in it. This will give the effect of a second sound source and sound waves from it will naturally interfere more or less with waves emitted from the front part of the diaphragm thereby causing distortion and lessened intensity.

Still another effect resides in the action of the vibrating column of air on the diaphragm itself. The column of air set in motion by the rear face of the diaphragm will of course be reflected by the walls of the enclosing casing and there will be certain frequencies at which strong resonant effects will be obtained thereby increasing the amplitude of the diaphragm vibrations. At certain other frequencies the entrapped air in the casing may be reflected in the correct phase relationship to exactly oppose the vibration of the dia-

phragm, thereby cutting down its amplitude of vibration considerably. While these effects are more noticeable at certain frequencies than at others it is obvious that they will be present in greater or lesser degree at most 55 of the frequencies at which the device operates. It will be clear that the combination of these effects, or in fact even one of the effects alone, will cause considerable distortion in the sound output and probably reduce 60 considerably the intensity of the output.

According to the present invention these effects are all overcome by a very simple expedient. If the enclosed cavity behind the diaphragm is lined with some sound absorbing material, such as felt for example, there will be substantially no possibility of the waves from the rear of the diaphragm being reflected from the walls of the casing and therefore, no tendency to resonant effects. 70 This material also, if properly chosen, will prevent the passage of sound waves through it and, therefore, obviate any tendency of the casing itself to vibrate. The sound emitted by the device so constructed will, therefore, 75 be free from distortion and greatly increased in intensity, giving a faithful loud reproduction of the original sound.

The invention is illustrated, by way of example, in the accompanying drawings in 80 which

Fig. 1 illustrates the operating mechanism of a loud speaker constructed in accordance with the invention.

Fig. 2 is a sectional view on line 2—2 of 85 Fig. 1 showing the construction of the lined casing wall, and

Fig. 3 is a cross section of a casing wall with a modified form of lining.

Referring to Fig. 1, the operating mechanism of a loud speaker of a well known type is shown comprising a base 1 on which is mounted a support 6, to which is fastened the operating mechanism of the loud speaker. The operating mechanism comprises a permanent magnet 3, held in place on the support 6 by the clamp 5. The vibrating armature 7 is suitably supported as shown and the operating coil 4 is mounted on the armature 7 and fastened to the vibratory cone 9 100

by means of the rod 8. The cone 9 has flanges provided at its outer edge which are fixed to flexible ring 10, clamped in place between the clamping rings 11. The outer or operative surface of the cone 9 communicates with the sound duct 12 which may be joined to any desired sound amplifying means, usually a horn. The operating mechanism is enclosed by a casing 2 which forms a closed cavity behind the diaphragm 9.

10 It is unnecessary to go into the theory of operation of the loud speaker mechanism as this is well known. It suffices to say that undulating currents in the coil 4 acting upon the field of the permanent magnets causes armature 7, coil 4 and attached diaphragm 9 to vibrate in sympathy with the current changes. The vibration of the diaphragm 9 will then, of course, reproduce the sounds 15 which originally caused the undulations of current in the coil 4.

The undesirable effects noted above are obviated in the device shown in the figure by lining the cavity behind the diaphragm with 20 sound absorbing material shown at 13. This, as pointed out above, prevents any resonant effects due to the presence of the closed chamber and also prevents any vibration of the casing 2, permitting it to act as a secondary 25 sound source.

It has been found that a felt lining as shown in Fig. 2 will eliminate all the undesirable effects but in order to obtain substantially perfect operation of the diaphragm, this felt would have to be of considerable thickness, probably an inch, which ordinarily would make the apparatus too bulky. It should be noted however, that a much thinner lining of felt or absorbing 30 material will substantially improve the operation of the device and it is not always necessary to make a covering of this thickness.

Fig. 3 shows a modification of a lining for the casing which is not unduly bulky and 35 which gives substantially the same results as a felt lining an inch thick. The lining shown in Figure 3 comprises a layer of lead foil 202 which is attached to the casing 201, and a layer of felt 203 which covers the layer 40 of lead foil. The layer of lead foil may be about 5 mils thick and the layer of felt may be about $\frac{1}{8}$ of an inch thick. It has been found that this gives substantially perfect 45 operation of the device from an acoustical point of view and that it is not so bulky as to make it objectionable from the manufacturing standpoint. The lead foil in this case forms a substantial rigid barrier which transmits and reflects sound waves very poorly, if at all, thereby making a thick layer 50 of felt unnecessary.

The device is illustrated and described in connection with a loud speaker having a completely enclosed cavity behind its diaphragm and this is the application in which the inven- 55

tion is most effective and will find its greatest use as, in this case the undesirable effects pointed out above will be at their maxima. The device, however, is not limited to this specific case as it can be equally well applied to a cavity behind the diaphragm which is only partially enclosed and could even be applied to an open diaphragm in which objects in the vicinity would tend to cause any of the effects which it is designed to prevent.

70 While I have shown the device in several very specific modifications, it is obvious that many other methods of putting it into effect will readily occur to those skilled in the art. The modifications described should therefore be taken in an exemplary and not in a limiting sense as I intend to be limited only as indicated by the scope of the following claims.

75 I claim:

1. An acoustic device comprising a sound emitting element, operating mechanism and supporting means therefor and a covering comprising a layer of non-vibratory metallic material and a layer of sound absorbing material on said supporting means.

80 2. An acoustic device comprising a sound emitting element, operating mechanism and supporting structure therefor and a covering comprising a layer of lead and a layer of felt on said supporting structure.

85 3. An acoustic device comprising a vibratile element, a casing enclosing the space at the rear of said element and a lining for said casing comprising a layer of non-vibratory metallic material and a layer of sound absorbing material.

90 4. An acoustic device comprising a vibratile element, a casing enclosing the space at the rear of said element and a lining for said casing comprising a layer of lead and a layer of felt.

95 5. An acoustic device comprising a vibratile diaphragm, a casing enclosing the space at the rear of said diaphragm and a sound absorbing lining for said casing.

100 6. An acoustic device comprising a vibratile diaphragm, means forming a substantially enclosed air space in back of said diaphragm, and a layer of fibrous material positioned in said enclosed air space for reducing the damping action of the entrapped air on said diaphragm.

105 7. An acoustic device comprising a vibratile diaphragm, means for preventing communication between the rear and the front of said diaphragm, and additional means positioned at the rear of said diaphragm for preventing the sound waves radiated from the rear of said diaphragm from substantially affecting said diaphragm, said additional means consisting of a layer of fibrous sound absorbing material.

110 8. An acoustic device comprising a vibratile diaphragm, a casing enclosing the space

at the rear of said diaphragm and forming a substantially closed air pocket, and acoustic damping material positioned in said air space for preventing the sound waves radiated from the rear of said diaphragm into said substantially closed air pocket from applying a damping action to said diaphragm, said acoustic damping means comprising a layer of felt applied to at least a substantial portion of said casing.

9. An acoustic device comprising a conical diaphragm, supporting means at the edge of said diaphragm, a structure to which said supporting means is attached, said structure forming with said supporting means and said diaphragm a substantially enclosed air space, and damping material positioned within said air space for reducing the reaction of the entrapped air in said air space against said diaphragm, said damping material consisting of a layer of fibrous material secured in back of said diaphragm.

10. An acoustic device comprising a vibratile diaphragm, a casing substantially enclosing the space at the rear of said diaphragm, means for securing said diaphragm to and directly mounting said diaphragm in said casing, and vibration damping material positioned within the enclosed space.

11. An acoustic device comprising a conical diaphragm, structure substantially encompassing the rear of said conical diaphragm, and a layer of sound absorbing material positioned within said structure.

12. An acoustic device comprising a conical diaphragm, structure encompassing the rear of said diaphragm, and a layer of felt within said structure.
